UNITED STATES PATENT OFFICE.

FREDERIC R. KNEIP, OF REVERE, MASSACHUSETTS, ASSIGNOR OF ONE-THIRD, BY MESNE ASSIGNMENTS, TO SAID FREDERIC R. KNEIP, TRUSTEE.

APPARATUS FOR CUTTING AND POLISHING PRECIOUS STONES.

SPECIFICATION forming part of Letters Patent No. 775,567, dated November 22, 1904.

Application filed February 3, 1904. Serial No. 191,788. (No model.)

To all whom it may concern:

Be it known that I, FREDERIC R. KNEIP, of Revere, in the county of Suffolk and State of Massachusetts, have invented certain new and useful Improvements in Apparatus for Cutting and Polishing Precious Stones, of which the following is a specification.

This invention is an improvement on the apparatus set forth and claimed in Letters Patent of the United States No. 698,521, granted to me April 29, 1902, the said apparatus comprising a stick to the outer end of which the stone to be cut is attached by wax, as usual, and a stick-holder suspended from an overhanging arm or support and pivoted thereto for movement about both a horizontal and a vertical axis, said stick-holder having means to hold the stick from turning, the apparatus as a whole providing for the accurate angular positioning of the stick about its own axis and for holding the same in correct angular position relatively to the usual lap or grinding wheel during the grinding and polishing operation, whereby the facets of the stone may be ground and polished accurately and evenly.

The present invention relates entirely to the stick-holder, which, as shown in my former patent above mentioned, comprises a body which is supported in such manner that it is movable about both a horizontal and a vertical axis, said body having a socket extending through it and a stick-receiving socket-piece fitted to turn in said socket, and thus permit the stick and the stone attached thereto to be adjusted to different positions relatively to the lap by a partial rotation of the socket-piece in the body of the stick-holder.

My invention consists, chiefly, in the provision of means for effecting an accurate and, if desired, extremely minute rotative adjustment of the socket-piece, so that the exercise of a high degree of judgment and skill on the part of the lapidary in rotatively adjusting the socket-piece is not required, the lapidary having only to move or rotate the socket-piece in accordance with a predetermined plan and having always at his disposal accurate means

for determining when the socket-piece has been properly adjusted for the formation of a given facet on the stone.

The invention also consists in certain incidental improvements, all of which I will now proceed to describe and claim.

Of the accompanying drawings, forming a part of this specification, Figure 1 represents a front elevation of a stick-holder embodying my invention and parts of the supporting mechanism for said stick-holder, said mechanism being the same as shown in the above-mentioned patent. Fig. 2 represents a top view of the stick-holder. Fig. 3 represents a section on line 2 2 of Fig. 1, showing the stick in place in the stick-holder and in its operative relation to the lap. Fig. 4 represents a section on line 4 4 of Fig. 3. Fig. 5 represents a side view of the stick detached from the holder.

The same reference characters indicate the same parts in all the figures.

In the drawings, 10 represents the body portion of the stick-holder, the same being preferably substantially disk-shaped or cylindrical. The said body is adapted to turn on a substantially horizontal axis, which is formed by pivots 11 11, inserted in arms 12 12, which are formed on a head-block 13, the latter being mounted to turn on a vertical axis or pivot 14. Said pivot is supported by an arm which overhangs the horizontal lap or grinding tool L. The construction thus far described is practically the same as that set forth in my above-mentioned Letters Patent, the body 10 of the stick-holder being adapted for movement about a horizontal axis—viz., the pivots 11 11—and a vertical axis—viz., the pivot 14—so that the stone 50, which is attached by the usual wax connection 51 to one end of the stick 52, inserted in the stick-holder, is adapted to assume a variety of angles and operative positions relatively to the lap L, all as fully described in the said patent. The body 10 of the stick-holder is provided with a socket 15, Fig. 3, which extends through the stick-holder and across the horizontal and vertical axis thereof, as shown in my former patent.

16 represents a socket-piece which is fitted to turn in the socket 15 and has a tapering bore formed to receive one end portion of the stick 52, the construction as regards the socket 5 and socket-piece being substantially like that shown in the said patent, in which is set forth the fact that the socket-piece is capable of being partially rotated, and thus varying the angular position of the stone relatively to the 10 lap to permit the stone to be adjusted to a series of positions for obtaining a series of facets. The socket-piece and stick are also provided with means whereby the stick may be engaged with the socket-piece in another 15 series of positions for obtaining another series of facets, the said means comprising a coupling member 17, affixed to the socket-piece 16, and a sleeve or collar 18, secured to the stick 52 and provided with a series of radial 20 notches 19, each of which is a coupling member adapted to engage the coupling member 17. The stick may therefore be coupled to the socket-piece and positively engaged therewith in either of a predetermined series of 25 positions.

In carrying out my present invention I combine with the said means for coupling the stick to the socket-piece means for rotating the socket-piece in the body 10 and for holding 30 said socket-piece in any adjustment to which it may be rotated, the means for rotating the socket-piece being such that the said piece may be given any desired rotative adjustment, even the most minute, to give the stick any desired 35 intermediate position, or, in other words, any position between the positions provided for by the said coupling members, so that the socket-piece and the stone may be adjusted with absolute accuracy without the exercise of a high 40 degree of skill or the exercise of extreme nicety of judgment on the part of the lapidary.

In the embodiment of my invention here shown the means for rotatively adjusting the socket-piece and for holding said socket-piece 45 at any desired position to which it may be adjusted comprise a worm-gear 20, affixed to the socket-piece, and a worm 21, journaled in bearings in the body 10 and meshing with the gear 20. It will be seen that the worm prevents 50 the rotation of the socket-piece excepting when the worm is rotated and that absolutely accurate predetermined rotative adjustment of the socket-piece is permitted by the coöperation of the worm and worm-gear. The shaft of the worm 21 is extended outwardly from one side of the body 10 and is provided with a knob or hand-wheel 22, by which it may be rotated. The body 10 is provided with a segmental graduated scale 23, 55 which coöperates with a finger or pointer 24, affixed to the socket-piece 16, in indicating the extent of rotative adjustment imparted to the socket-piece. The said pointer is preferably a part of the arm or coupling member 60 17, which detachably engages the socket-piece

with the sleeve 18 of the stick. The scale 23 is adjustable longitudinally to compensate for variations in the alignment of different lapidary-benches with which the apparatus may be used. The scale 23 is supported by a segmental seat 25, formed on the body 10, and is secured to said seat by a screw 26, passing through a segmental slot 27, formed in a flange affixed to the scale 23. When the screw is loosened, the scale 23 may be adjusted longitudinally to a limited extent and may then be secured by tightening the screw. 70 75

The socket 15 in the body 10 is enlarged at one end to receive the portion of the socket-piece to which the worm-gear 20 is attached. 80 The socket-piece is provided with a shoulder bearing against the inner end of the enlarged portion of the socket, as shown in Fig. 3, said shoulder being preferably one side of the worm-gear 20. The extent to which the 85 socket-piece can enter the body 10 is therefore limited. The socket-piece is removable from the body 10 by an outward endwise movement. Said movement is prevented, however, by the worm 21 when the latter is in place, 90 the engagement of the worm with the worm-gear preventing endwise outward movement of the socket-piece, and therefore locking the socket-piece to the body 10. The worm is detachably connected to the body 10, so that 95 it may be removed to permit the removal of the socket-piece. One end of the worm is provided with a reduced journaled portion 27, which is fitted in a bearing 28 at one end of a cavity 29, formed for the reception of the 100 worm 21. The opposite end 30 of said cavity is enlarged and provided with an internal screw-thread, with which is detachably engaged an externally-threaded bearing-piece 31, in which the extension 32 of the worm-shaft is journaled. When the bearing-piece 31 is removed, the worm 21 may be withdrawn from the cavity 29, thus releasing the socket-piece 16 and permitting the latter to be withdrawn from the body 10. The bearing-piece 31 may be provided with orifices arranged at opposite sides of its center for engagement with the prongs of a spanner, whereby the said bearing-piece may be rotated to apply it to and remove it from the body 10. 105 110 115

It will be understood that the general operation of the apparatus is the same as described in my above-mentioned Letters Patent, to which reference may be had for a complete description. 120

I desire to call attention to the fact that the two means for rotatively adjusting the stick—viz., the coupling members and the worm-gear and worm—enable the stick to be adjusted both quickly and accurately, a quick adjustment being permitted by the coupling members, which are connected and disconnected by endwise movements of the stick, while a minute or micrometric additional adjustment is permitted by the worm-gear and worm, the 125 130

last-named adjustment turning the stick to any desired intermediate position and holding it in said position.

While I have herein referred to the gem-holding part 52 as a "stick," I do not limit myself to a gem-holder made of wood, it being obvious that any other suitable gem-holding device adapted for insertion in the socket 16 may be employed.

10 I claim—

1. In an apparatus of the character specified, a stick-holder comprising a body movably supported, a socket-piece mounted to turn in said body, a stick movable endwise in the 15 socket-piece, the said stick and socket-piece being provided with means made operative by an endwise movement of the stick for coupling the stick to the socket-piece in either of a predetermined series of positions, and 20 means for rotatively adjusting and retaining the socket-piece to give the stick any intermediate rotative adjustment.

2. In an apparatus of the character specified, a stick-holder comprising a body movably supported, a socket-piece mounted to turn in said body, a stick movable endwise in the socket-piece, the said socket-piece having a coupling member, while the stick has a sleeve 25 provided with a circular series of complementary coupling members, each of which is adapted by an endwise movement of the stick to engage the coupling member on the socket-piece to hold the stick in either of a predetermined series of positions, and means for rotatively adjusting and retaining the socket-piece to turn the stick to any intermediate position.

3. In an apparatus of the character specified, a stick-holder comprising a body movably supported, a socket-piece mounted to turn in said body, a stick movable endwise in the socket-piece, the said stick and socket-piece being provided with means made operative by an endwise movement of the stick for coupling the stick to the socket-piece in either of 45 a predetermined series of positions, a worm-

gear affixed to the socket-piece, and a worm journaled in the body and meshing with said gear.

4. In an apparatus of the character stated, 50 a stick-holder comprising a movably-supported body having a socket, a stick-receiving socket-piece fitted to turn in said socket and having a worm-gear, a worm journaled in the body and meshing with the said gear, and 55 means for detachably securing the worm to the body, the socket-piece being removable from its socket when the worm is removed.

5. In an apparatus of the character stated, 50 a stick-holder comprising a movably-supported body having a socket, and a cavity extending crosswise of said socket and communicating therewith, said cavity having an enlarged, internally-threaded end portion at one end, and a bearing at the opposite end, a stick-receiving socket-piece fitted to turn in said socket and provided with a worm-gear, an externally-threaded bearing-piece detachably engaged with the thread of the said cavity, and a worm journaled in said bearing and 70 bearing-piece and held thereby in engagement with the said worm-gear, the worm being removable upon the removal of the said bearing-piece.

6. In an apparatus of the character stated, 75 a stick-holder comprising a movably-supported body having a socket, and a segmental seat concentric with the socket, a stick-receiving socket-piece fitted to turn in said socket and provided at one end with an arm projecting 80 from one side of the socket-piece, a graduated segmental scale-piece adjustably mounted on said seat and arranged to coöperate with said arm, and means for securing the scale-piece to the body in any position to which it may be 85 adjusted.

In testimony whereof I have affixed my signature in presence of two witnesses.

FREDERIC R. KNEIP.
